CHARLES B. STRAVS AND JOHN N. JAGER, OF MINNEAPOLIS, MINNESOTA,
ASSIGNORS OF ONE-THIRD TO ANTHONY HUHN, OF MINNEAPOLIS,
MINNESOTA.

PROCESS OF FORMING PIPE IN CONTINUOUS LENGTHS.

SPECIFICATION forming part of Letters Patent No. 777,562, dated December 13, 1904.

Application filed February 23, 1904. Serial No. 194,695. (No specimens.)

To all whom it may concern:

Be it known that we, CHARLES B. STRAVS and JOHN N. JAGER, of Minneapolis, in the county of Hennepin and State of Minnesota, have invented certain new and useful Improvements in Processes of Forming Pipe in Continuous Lengths, of which the following is a specification.

The object of this invention is to provide a new process of forming pipe or tubing in continuous lengths with a series of wires extending lengthwise thereof and embedded therein, said wires being arranged separately or being formed into a fabric and being for the purpose of strengthening the formed article.

The invention consists generally in distributing metal in molten condition by centrifugal force upon the inner surface of a cylindrical mold, cooling it, and causing it to solidify before it leaves the mold, and embedding in the metal while in molten condition a series of wires or similar articles which remain therein when the metal becomes solidified and strengthen the formed article.

The invention consists, further, in the new process hereinafter described, and particularly pointed out in the claims.

In the accompanying drawings, forming part of this specification, Figure 1 is an outline-section of an apparatus that may be employed for carrying out our invention. Fig. 2 is a plan view of the same.

In carrying out our process we distribute the metal in a molten condition by centrifugal force over the inner surface of a distributing-chamber 4, as shown in Fig. 1, in the manner described in our application, Serial No. 187,475, filed January 2, 1904. From this receptacle, reservoir, or chamber we distribute the molten metal upon the inner surface of a cylindrical mold 5. To form a pipe or hollow shaft, the metal is kept against the inner surface of the mold by centrifugal force, as described in our said application.

At the outlet or discharge end of the mold, which is preferably the bottom, the mold being usually arranged in an upright or vertical position, we provide a support 9, upon which

the end of the pipe being formed rests or to which it is secured, as hereinafter described. 50 This support is arranged to move away from the end of the mold as the article is being formed. We do not in this application show the means for holding and moving the support 9, as we have shown and described suitable means for this purpose in our application filed January 19, 1904, Serial No. 189,767. The upper or inlet portion of the mold will be heated and the lower or outlet portion cooled. This may be done in the manner described in 60 our said application of January 2, 1904, Serial No. 187,475, and our application of January 19, 1904, Serial No. 189,767.

Above the reservoir or distributing-chamber we provide a series of spools 11, upon each 65 of which is wound a suitable length of wire 13. This wire may be solid or hollow in the form of small flexible tubing. This wire is led from the spools 11 through openings at the upper end of the mold (see Fig. 2) into 70 and through the mold, and the ends of the wire are connected to the support 9. Sufficient tension is brought upon the wires in drawing them through the mold to cause them to be properly distributed in the article being 75 formed. If preferred, the wires may be supported by other means than the spools, and also, if preferred, the wires may be formed into or constitute part of a netting or wire fabric. 80

In carrying out our process the wire is first put in place, and each wire is carried through the mold and connected to the support 9. The metal is then reduced to a molten condition either in the reservoir or before being placed 85 therein, and this molten metal is then fed into the mold and passes downward therein until it reaches the lower part of the mold and the support 9. The wires 13 are surrounded and embedded in the metal. We find it 90 preferable not to cool the lower part of the mold until the metal has reached the support 9. The lower part of the mold is then cooled, and the part of the metal therein is solidified. The support is then moved away from the 95 mold in a straight line parallel with the axis

of the mold, and thereby the solidified part of the metal and the lower portions of the wires are drawn out of the mold. The wires are drawn off from the spools and through the mold, and additional metal passes into the mold. The metal enters the mold in a molten condition and leaves it solidified and with the wires embedded therein. A tube or pipe may thus be formed, which may be made of any desired length. These wires strengthen the formed article, being embedded directly in the material thereof. Moreover, by moving the support the pull exerted is upon the wires rather than upon the article. This prevents any cracking or breaking of the material of the article itself and causes the article to be drawn through the mold with the embedded wire, to which the pulling force is applied.

We do not make any claim to the apparatus in this application. While we usually employ this process in forming metal articles, it may be employed for forming articles of glass or other material.

We claim as our invention—

1. The process of forming articles in continuous lengths, consisting in passing a series

of wires through a suitable mold, distributing molten metal by centrifugal force over the inner surface of said mold and embedding said wires therein, allowing said metal to solidify and drawing the wires and the solidified metal from the mold. 30

2. The process of forming articles in continuous lengths, consisting in passing a series of wires through a suitable mold, securing 35 their ends to a suitable support, distributing molten metal by centrifugal force over the inner surface of said mold, allowing said metal to solidify, whereby the wires become embedded in the metal, moving the support 40 away from the mold and thereby drawing the metal and the embedded wires from the mold and supplying additional molten metal to the mold as the solidified metal is drawn therefrom. 45

In witness whereof we have hereunto set our hands this 16th day of February, 1904.

CHARLES B. STRAVS.

JOHN N. JÄGER.
